F. BRADLEY

MATTRESS

Filed Jan. 26, 1924

FIG. 1.

FIG. 2.

INVENTOR
Frank Bradley
By Frederick C. Bromley

ATTY.

UNITED STATES PATENT OFFICE.

FRANK BRADLEY, OF TORONTO, ONTARIO, CANADA.

MATTRESS.

Application filed January 26, 1924. Serial No. 683,807.

To all whom it may concern:

Be it known that I, FRANK BRADLEY, a subject of the King of Great Britain, and resident of 86 Pinewood Avenue, in the city of Toronto, in the Province of Ontario, in the Dominion of Canada, having invented certain new and useful Improvements in Mattresses, do hereby declare that the following is a full, clear, and exact description 10 of the same.

The invention relates to improvements in mattresses as described in the present specification and shown in the accompanying drawings that form part of the same.

15 The invention appertains to the novel construction and arrangement of parts by which a mattress composed of two connected sections may readily have each component section independently reversed for purposes of 20 airing without changing the relative position of each section one with the other or necessitating releasing of their connections.

A distinctive feature of this invention is also provided in that the parts of this mattress can be conveniently folded one upon 25 the other rendering it compact for handling and convenient for transportation.

Hitherto sectional mattresses have been proposed wherein provisions were made to 30 unite the sections, in some instances the connection being in the form of a hinge, whilst in others means are provided to permit of the separation of the sections. Whilst these objects are attained in the present invention, 35 it will be manifest that the additional features hereinbefore recounted together with the specific construction hereinafter described constitute definite improvements in the art.

40 Referring to the drawings, Figure 1 is a perspective view of the mattress embodying the invention.

Figure 2 is a view of one end of the mattress illustrating a section in the act of its 45 being turned.

Like numerals of reference indicate corresponding parts in each figure throughout the drawings.

In the drawings, 1 and 2 denote two separate 50 sections of a mattress, such sections extending longitudinally with each other and being of an equal width.

The corresponding ends of the aforesaid sections are secured together by means that are entirely symmetrical and a description, 55 therefore, of one of such sections will serve for both.

3 and 4 are pivots centrally affixed to the respective ends of two mattress sections, said pivots comprising pins 5 and 6 secured 60 to the walls of the ends by means of comparatively large heads. Mounted upon each of these pins 5 and 6 are rings 7 and 8 which are held thereon by disks 9 and 10 of a greater diameter.

65 11 is a strap passing through the rings 7 and 8 and having its termini connected one to the other by a buckle 12.

It will be manifest from the foregoing description that one mattress section is so 70 connected to the other that same is free to swing thereabout, and also that by the central disposition of such connections each of such sections are free to rotate about their pivots. Thus, it is simply necessary to reverse first one section and then the other to 75 achieve the complete turning of the mattress, thus involving less effort and saving considerable time.

What I claim is:—

1. A mattress comprising two sections extending longitudinally one with the other, and being of an equal width; pivots affixed centrally of the ends of same, straps connecting together the pivots of corresponding 85 section ends for the purpose of permitting reversal of each individual section without detaching one from the other, and means interposed in said straps to adjust the length thereof.

2. A mattress comprising two sections extending longitudinally one with the other, and being of an equal width; pivots affixed centrally of the ends of same, straps connecting together the pivots of corresponding 95 sections ends for the purpose of permitting reversal of each individual section without detaching one from the other, and buckles interposed in said straps to adjust the length thereof.

3. A mattress comprising two sections extending longitudinally one with the other and being of an equal width, pins affixed centrally of the ends of same, rings mounted

upon said pins, discs secured to said pins to retain the rings thereupon, straps passed through the rings of corresponding section ends for the purpose of permitting reversal of each individual section without detaching one from the other and buckles connecting the termini of each strap together.

Signed at Toronto, Ontario, Canada, this 16th day of January, 1924.

FRANK BRADLEY.
